UNITED STATES PATENT OFFICE.

CHARLES H. QUINN, OF ROANOKE, VIRGINIA.

TENSIONING DEVICE FOR CAR-DYNAMOS.

1,318,407.

Specification of Letters Patent.

Patented Oct. 14, 1919.

Application filed May 23, 1918. Serial No. 236,118.

To all whom it may concern:

Be it known that I, CHARLES H. QUINN, a citizen of the United States, residing at Roanoke, in the county of Roanoke and 5 State of Virginia, have invented certain new and useful Improvements in Tensioning Devices for Car-DYNAMOS; and I do hereby declare the following to be a full, clear, and exact description of the invention, such as will 10 enable others skilled in the art to which it appertains to make and use the same.

The invention relates to car axle-driven dynamos and more particularly to means for automatically tensioning the driving belt 15 which connects the pivotally supported generator to the car axle.

The principal object of my invention, generally stated, is to provide a belt tensioning device carried by the car framing and acting 20 through differential means to maintain a constant tension on the belt in all positions of the dynamo.

Another object of my invention is to provide a belt tensioning device which avoids 25 the use of springs as the means for maintaining the belts in driving relationship and substitutes therefor a gravity acting means for maintaining at all times a constant tension upon the dynamo belt.

30 There are many other features of the invention which will be pointed out in connection with the detailed description of the specific embodiment thereof which have been illustrated in the accompanying drawings, 35 in which—

Figure 1 is a view in side elevation of a portion of a car underframe, showing the application of the invention thereto.

Fig. 2 is a fragmentary view in elevation 40 of an axle-driven dynamo and the supporting cradle,

Fig. 3 is a transverse vertical sectional view taken on the line 3—3 of Fig. 1, looking toward the dynamo, and

45 Fig. 4 is a fragmentary view in elevation of a slightly modified construction.

Throughout the specification and drawings like parts are designated by like reference characters.

50 The center sills of a car underframe are designated by the numerals 1, 1 and 2 is one of the wheels of a car truck which is shown by dotted lines.

To the truck frame is connected in any 55 suitable manner the suspension bars 3, only one of the latter being illustrated, and piv-

otally supported on the suspension bars 3 is the dynamo supporting frame or cradle 4. The manner of pivotally supporting the cradle 4 from the bars 3 is fully described 60 and claimed in my copending application Serial No. 188,141, filed October 29, 1917, and hence need not be described in detail.

It will be sufficient to state that each bar 3 is provided with a saddle 5 and that the 65 upwardly projecting arms 6 of the cradle 4 are each provided with a loop-shaped member 7, each of which is adapted to be pivotally supported by the adjacent saddle 5 by means of the pivotal connection 8. 70

To the under face of the cradle 4 and preferably in line with the pulley 9 of the dynamo or generator 10, there is provided an angular shaped rearwardly extending bracket 11 which is preferably riveted to the 75 cradle 4 as shown at 12. To the outwardly extending end of the bracket 11 is pivotally connected a jaw member 13 by means of the pin 14, the said jaw member 13 being connected in any suitable manner to the 80 end of a flexible member 15, which may and preferably is formed as a wire rope or cable.

At a point in rear of the normal position of the cradle, the car underframe is provided with a plurality of alined openings 16 85 which are adapted to form the journal bearings for a shaft 17. These openings may, for convenience, be formed in the center sills 1, 1 as shown. Intermediate the said sills the shaft 17 is provided with an eccentric pulley 18, which is preferably adjustably connected to the said shaft by any of the ordinary ways commonly employed in this type of construction. A pair of sleeves 19 may be provided, each of said sleeves being 90 adapted to be loosely received on the said shaft 17 between one of the said sills and the adjacent hub 20 of the pulley 18. 95

One end of the shaft 17 is adapted to extend through one of the openings 16 so as to 100 project a short distance beyond the outer face of the adjacent sill and on the projecting end 21 of the shaft is mounted an eccentric pulley 22. This pulley is also adjustably fixed to the shaft 17 in any suitable or convenient manner. 105

To the depending portions of the center sills 1 is connected a weight guide 23 which may and preferably does comprise a U-shaped strap having the upwardly extending 110 arms 24 thereof positioned in alinement with the plane of the pulley 18. The weight

guide 23 is preferably maintained in position by means of the V-shaped brackets 25 and 26 and the angle bars 27 and 28.

Connected to the pulley 18 in any convenient manner is a flexible member or cable 29 which is adapted to lie within the groove 30 of the pulley and extend downwardly therefrom between the arms 24 of the weight guide 23. To the free end of the cable 29 is connected the weight 31 the end faces of which are recessed as at 32 to receive the arms 24 of the weight guide.

The inner end of the cable 15 is connected to the pulley 22 within the groove 34 thereof in any convenient manner.

The pulley 9 of the generator or dynamo 10 is operatively connected to the car axle pulley 9^a by means of the belt 33. In the drawings the parts 9^a and 33 are indicated 20 by dotted lines.

The eccentric pulleys 18 and 22 are connected to the shaft so that when the generator cradle 4 lies in a vertical plane the weight arm of the pulley 22 will equal in 25 length the power arm of the pulley 18 and the eccentricities of the pulleys are such that when the cradle swings toward the truck the weight arm of the pulley 18 decreases but when the cradle swings in the opposite 30 direction from the vertical the weight arm of the pulley 18 increases.

The differential action above described maintains at all times a constant tension upon the belt 33. For when the cradle 35 swings toward the truck frame the weight of the generator acts to swing the generator back to the vertical and hence tends to tighten the belt 33 and hence less power is required by the tensioning device, but when the generator swings away from the truck the tendency to return to the vertical results in loosening the belt 33 unless more tension is applied by the tensioning device.

The result may be obtained by employing 45 the construction shown in Fig. 4 wherein levers 18^a and 22^a are shown as replacing the eccentric pulleys disclosed in the other views. The said levers 18^a and 22^a forming a belt crank arrangement wherein the power 50 and weight arms are increased or diminished

automatically as required to maintain a constant belt tension.

As clearly shown in Fig. 1 the tension on the belt 33 may be adjusted to any desired degree by means of the additional weights 55 35 which are adapted to be positioned within the weight guide 23 and to be supported by the weight 31.

By the foregoing description of the device I do not intend to limit myself to the precise 60 details shown, and it is to be understood that the terms employed are to be understood in their descriptive and not in their limiting sense.

What I claim is:

65

1. In a car underframe, the combination with a pivotally supported generator which is operatively connected to the car axle by means of a belt, of means adapted to maintain a constant tension upon the generator 70 belt under all service conditions.

2. In a car underframe, the combination with a belt driven pivotally supported electric generator, of differentially acting means for applying a substantially constant tension to said generator belt under all service 75 conditions.

3. In a car underframe, the combination with a belt driven pivotally supported electric generator, of differential means supported by the car underframe for maintaining a substantially constant tension upon the 80 said generator belt.

4. In a car underframe, the combination with a car truck having a belt driven electric generator pivotally supported therefrom, of means for maintaining a constant tension on the said generator belt, said means including differential means pivotally supported by the said underframe. 85

5. In a car underframe the combination with a pivotally supported belt driven dynamo, of differential means for maintaining a substantially constant tension on the said 90 dynamo belt said means including a flexible cable connected to the dynamo support and to a member attached to the underframe.

In testimony whereof I affix my signature.

CHARLES H. QUINN.
